UNITED STATES PATENT OFFICE.

WILLIAM MORRISON TAYLOR, OF ATLANTA, GEORGIA.

WEIGHING-SCALE.

SPECIFICATION forming part of Letters Patent No. 357,426, dated February 8, 1887.

Application filed April 22, 1886. Serial No. 199,846. (No model.)

To all whom it may concern:

Be it known that I, WILLIAM MORRISON TAYLOR, a citizen of the United States, residing at Atlanta, in the county of Fulton and 5 State of Georgia, have invented certain new and useful Improvements in Weighing-Scales; and I do declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

15 This invention relates to that class of weighing-scales in which a weight counterbalances the article weighed; and it consists in mechanism whereby the counterbalancing weight has an increasing leverage as it is raised, and in 20 dials for indicating and registering the weight, as will be hereinafter fully described, and then specifically claimed.

In the accompanying drawings, Figure 1 is 25 a perspective view of a portion of a floor-scale with registering device attached. Fig. 2 is a side view of the top end of the registering device. Fig. 3 is a side view, partly in section, of a portion of the bottom end; and Fig. 4 is a horizontal section on the line X Y, Fig. 3. 30 Fig. 5 is a view of the back side of top end of bracket.

In the drawings, A represents a scale-beam; B, a pendent bracket attached to the frame of the scale C.

35 D is a stud projecting from the bracket. E is a sleeve revolving on said stud. On the outer end of this sleeve is a scroll-shaped cam, F. Attached at one end to the scale-beam A and at the other to the sleeve E is a tape, G; 40 and to the cam F is attached one end of the tape H, which is held by the plug h, to the other end of which tape H is attached the weight I. The shaft J, passing through a bearing in the pendent bracket, is provided on its 45 inner end with the wheel K, on the side of which is the stud L. On the outer end of the shaft J is the lever M.

N is a swinging frame pivoted to the pendent bracket, an arm of which frame carries the 50 roller k, which engages with the cam K. The pulling coiled spring n is attached at one end

to the frame N and at the other to the pendent bracket B. In the side of this frame N are bearings for the shafts O P Q, and to one of the sides the stud for the wheel R. The wheel 55 R is attached to a sleeve, s', on the stud s'', and on the same sleeve is the friction-gear s', which engages with the friction-gear S on the sleeve E. The gear R engages with the pinion k' on the shaft Q, the pinion k' on the shaft 60 Q engages with the spur-wheel p on the shaft p', and the pinion p'' on the shaft P engages with the spur-wheel p''' on the shaft O. On one end of each of the shafts O P Q are pointers 1 2 3, and on the outer side of the frame, 65 under each of the pointers 1 2 3, is a dial, the one under the pointer on the shaft Q being preferably divided into one hundred equal parts, representing pounds and marks for such fractional parts of a pound as may be desired, 70 and the dial under the pointer on the shaft P is laid off so as to register one on every revolution of the shaft Q, and the dial under the pointer on the end of the shaft O to register one on every revolution of the shaft P.

75 The beam of the scale is held down by the contact of the stud L while the load is being placed on the scale. The cam K is revolved one half-turn, or as much as is necessary to allow the beam to rise by the lever M in the 80 direction indicated by the arrow in Fig. 5. This movement of the cam allows the roller k, Fig. 2, to rise before releasing the beam A, which brings the friction-gears S and s', by means of the coiled spring n, Fig. 3, in contact 85 before any movement takes place in the beam. The tape G, being wound about once around the sleeve and fastened at the end only, will cause the sleeve to revolve as the beam rises. The tape H, being attached at or near the center of revolution of the cam F, would be wound up on the cam by this revolution of the sleeve, to which the cam is attached, and offer increasing resistance. It is obvious that the beam 90 will rise until the resistance offered by the weight I is exactly equal to the force actuating the beam, and consequently the sleeve will revolve a distance in proportion to the force actuating the scale-beam, which motion is transmitted to the pointers by the friction-gearing S and s', and is indicated by the pointers on the dials.

Before the article weighed is removed the cam K should be turned to its original position in the direction indicated by the arrow, Fig. 2, which will depress the roller k, removing the friction-gearing from contact before the beam shall have been depressed, and the weight allowed to turn the cam and sleeve back to their original positions. The pointers would indicate on the dials the weight of the article thus weighed, and the friction-gears, not being in contact when the cam was allowed to turn back to its original position, will stand at that point, which operation being repeated will carry the pointers forward each time in proportion as the article weighed will raise the weight, thus indicating the weight of any number of drafts until the pointer on the shaft O shall have made an entire revolution.

If it is desired to have the weight of each draft indicated separately and not aggregated, the weight would be noted before the beam was depressed by the cam K. In depressing the beam the cam K should be turned in the direction opposite to that indicated by the arrow, Fig. 2, which will not release the contact of the friction-gears, and will cause the pointers to revolve back to their original position.

Having thus described my invention, what I claim as new, and desire to secure by Letters Patent of the United States, is—

1. In a registering-scale, the beam A, the tape G, the revolving sleeve E, the cam F, and the tape H, and the attached weight I, combined and operating substantially as described.

2. In a registering-scale, the combination of the beam A, the tape G, the revolving drum E, provided with a counterpoise which shall have increasing resistance as the beam rises, and the friction-gears S and s, and a series of dials arranged to indicate the weight, substantially as shown, and for the purpose specified.

3. In a registering-scale, the combination of a swinging frame pivoted to the bracket B, and carrying the registering device, the friction-gears that actuate said registering device, and the roller k, the friction-gear S, arranged to revolve in proportion to the load on the scale, the cam K, and stud L, arranged to permit the contact of the friction-gears before releasing the beam, substantially as shown and described.

In testimony whereof I affix my signature in presence of two witnesses.

WILLIAM MORRISON TAYLOR.
